UNITED STATES PATENT OFFICE.

JOSEPH B. STRAUSS, OF CHICAGO, ILLINOIS.

ELECTRIC-RAILWAY SYSTEM.

1,177,551.

Specification of Letters Patent.

Patented Mar. 28, 1916.

Application filed March 30, 1908. Serial No. 424,028.

To all whom it may concern:

Be it known that I, JOSEPH B. STRAUSS, a citizen of the United States, residing at Chicago, in the county of Cook and State of Illinois, have invented a certain new and useful Improvement in Electric-Railway Systems, of which the following is a specification.

This invention relates to electric cars, and 10 has for its object to provide a new and improved system and arrangement for operating the same.

The invention is illustrated in the accompanying drawings, wherein—

15 Figure 1 is a side elevation of a portion of a car illustrating my invention; Fig. 2 is a cross sectional view through the track showing the construction of the conducting system; Fig. 3 is a plan view of the track; 20 Fig. 4 is a diagrammatic view showing the circuits on the car; Fig. 5 is a sectional view through the conduit and contact device.

Like letters refer to like parts throughout the several figures.

25 One of the objects of my invention is to provide a conducting and operating system for electric cars, wherein there will be no live conductors exposed beyond the boundaries of the car.

30 Referring now to the accompanying drawings, I have shown a portion of a car 1, located upon any desired form of track, and provided with a suitable operating electric motor or motors and controlling apparatus.

35 Beneath the pavement and between the rails 2 of the track is a suitable conduit 3 which may be made of porcelain, concrete or any other suitable material, preferably a non-conductor of electricity, the conduit being 40 preferably water-tight. Within this conduit or passageway is an electric conductor 4 preferably continuous. This conduit or passageway is preferably entirely closed so that no part of the conductor is exposed or

45 can be tampered with. The closing of the conduit may be arranged in any desired manner, as, for example, by means of a series of closing or pavement sections 5 which extend from rail to rail, and which are re- 50 movably attached in position, but which entirely and completely close the conduit when in position. A series of exposed or external conductors 6 are arranged preferably between the rails and end to end, all of said

55 exposed conductors being electrically disconnected from each other, and separated at

their ends by either an air space or some suitable insulating material. These separated conductors may be of any desired length, but are preferably shorter than the 60 length of the car. These external or exposed conductors are fastened in position in any desired manner, and each of them is connected by an electrical connection 7 with a stationary concealed contact 8 located in the 65 conduit, the several contacts 8 being preferably arranged substantially equal distances apart.

Within the conduit 3 is a concealed or internal contact device 9 which moves with 70 the car, but is entirely disconnected therefrom, and has no part exposed with which pedestrians or animals may come into contact. This contact device when the car is moving engages the continuous conductor 4 75 and the various stationary contacts 8 so as to successively and electrically connect the continuous conductor with said stationary contacts. This contact device 9 is somewhat longer than the distance between the stationary contacts 8 so that it will engage one contact before leaving the other and thus successively connect the exposed conductor 6 with the continuous conductor 4, and hence the source of electrical supply. The distance 85 between the contacts 8 and the length of the conductors 6 is preferably such that no portion of any of the conductors 6 will be exposed beyond the boundaries of the car, while connected to the source of electric supply. The contact device 9 may be constructed in any desired manner. As illustrated in Fig. 2 this contact device is made up of two parts which are removably fastened together at the top, and which are provided at the 90 bottom with laterally extending projections, one of which engages the contacts 8 and the other the conductor 4. The conduit is shaped to receive these projections, and by dividing the contact device into two parts removably 95 connected together it can be inserted in the conduit, and will permit the use of a conduit much smaller than could be used if the contact device was in one piece. The conductor 4 is held in proper position in any desired 100 manner, as by means of the supports 10. The contact device 9 is preferably provided at the bottom with the protecting pieces 11 of some suitable material. Fastened to the car is an exposed contact device 12 which 105 may be a brush or a wheel or any other suitable means and which engages the conduc-

tors 6 as the car moves along the track. By means of this contact device the current is carried to the motor on the car, and also to a horse-shoe-shaped electromagnet 13 which is located above the conduit 3, and arranged to attract the concealed or internal contact device 9 so as to lift it into its contact position, electrically connecting the contacts 8 and the continuous conductor 4, and at the same time carry it along with the car. When the electromagnet is de-energized the contact device drops to the bottom of the conduit so as to break the electrical connection. The circuits on the car are arranged to keep the electromagnet in the circuit at all times, even when the motor is cut out of circuit to stop the car. This result may be secured in any desired manner. As shown in Fig. 4 the exposed contact device 12 on the car is connected by conductor 14 with the motor 15 which is provided with a controller 16 of any desired description, the connection 17 then running to ground. The electromagnet 13 is connected across the circuit in multiple with the motor so that when the current through the motor circuit is shut off it will still pass through the electromagnet. I prefer to provide a secondary battery 18 and have it connected up in such a manner that it will be charged by the current under ordinary conditions, and will act to energize the electromagnet in case the current in the line should for any reason cease, thus preventing the concealed contact device from being dropped while the car is in motion, and thus getting out of the field of influence of the electromagnet.

The exposed conductor it will be noted, is at one side of the main or concealed conductor, and is therefore, out of the direct field of the magnet which acts on the concealed contact, and the magnet, therefore, acts directly upon this concealed contact through the non-magnetic material of which the pavement sections 5 are made. It will further be noted that these pavement sections which form a cover for the conduit, extend from rail to rail across the space between them. This position of the exposed conductor out of the path of the magnet on the car permits the magnet to act with its maximum effect upon the concealed contact, there being no magnetic material between the two to take up the magnetism. This magnet forms, as it were, means on the car for governing or controlling the concealed source of supply and the exposed sectional conductor is out of the path of this means.

The conduit is made up of a series of sections end to end which are sealed up by the pavement pieces, each section having the exposed or external conductor engaged by a part on the passing car, such conductor having projections into the interior of the section of the conduit, with which it is associated, there being an automatic device within such sections by which the external conductor is connected with the source of the current as the part on the car engages said external conductor. The concealed contact device acts as an armature to the magnet on the car, and connects and disconnects the motor on the car with the concealed source of supply in the conduit. The external current bearing sections of the exposed conductor are normally inert, and are connected with the internal current bearing part, the internal armature being adapted to move with the car and connecting the two together.

I claim:

1. A contact device comprising two angular parts removably fastened together with laterally exterior projecting contact parts fixed with relation thereto.

2. The combination with an electric car having a motor thereon of a magnet on the car, a conductor extending along the path of the car, a contact device detached from the car and controlled by said magnet, said contact device comprising two angular parts removably fastened together with laterally exterior projecting contact parts fixed with relation thereto and adapted to be brought into contact with said conductor by the attractive power of the magnet.

3. A traveling closer for controlling an electric circuit comprising a thin metal plate having its middle portion bent upwardly and its edges bent outwardly, said edges forming the contact faces.

4. The combination with an electric car having a motor and a magnet thereon of separated conductors below the car and separate from the car and controlled by said magnet, said contact device comprising a thin sheet of metal bent upwardly at its middle to bring it into proximity to said magnet, the lower edges bent outwardly to engage said conductors.

JOSEPH B. STRAUSS.
